UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

METAL-REDUCING MACHINE.

1,187,729.

Specification of Letters Patent. Patented June 30, 1916.

Application filed October 21, 1915. Serial No. 57,102.

To all whom it may concern:

Be it known that I, BENGT M. W. HANSON, a citizen of the United States, residing at Hartford, in the county of Hartford and State of Connecticut, have invented certain new and useful Improvements in Metal-Reducing Machines, of which the following is a specification.

This invention relates to metal-reducing machines.

While my improvements are susceptible of incorporation in machines of various kinds of the type noted and others, they are of especial utility when embodied in a grinding-machine, and as one specific illustration I might mention what is known as a "spotting machine." I provide a construction wherein the tool and the work can be substantially and solidly supported and wherefore the organization comprises a minimum number of joints, thus insuring simplification without in any wise affecting the efficiency or accuracy of the machine.

The foregoing is a brief outline of some of the principal objects attained.

Others will be brought out in the following description wherein I will set forth in detail that particular form of embodiment of the invention which I have selected for illustration in the drawings accompanying and forming part of the present specification. This showing is provided to enable those skilled in the art to practice the invention. I do not limit myself thereto, but may depart therefrom in several respects within the scope of the invention defined by the claims following said description.

Referring to said drawings: Figure 1 is a front elevation of a machine involving my invention. Fig. 2 is an end elevation of the same as seen from the right in Fig. 1. Fig. 3 is a transverse section on the line 3—3 of Fig. 2, looking in the direction of the arrow. Fig. 4 is a detail view illustrative of a feed nut and a feed screw. Fig. 5 is a like view showing a portion of an adjusting wheel and a scale and pointer usable in conjunction therewith. Fig. 6 is a cross section on the line 6—6 of Fig. 2.

Like characters refer to like parts throughout the several views, Figs. 3 and

4 being on a scale larger than the other figures.

The machine comprises in its make-up two carriers, one of which sustains the tool 5 which in the present case is a grinding wheel, and the other of which sustains the work. The base or bed 2 answers satisfactorily as a carrier for the tool, while the carrier 3 upholds the work of whatever nature 60 it may be. When as in the construction shown the machine is adapted for "spotting" as it is known, the work will generally but not necessarily be of cylindrical form, for example a rifle or a gun barrel. 65 The tool such as the grinding wheel 4 is not only heavy but is subjected to some vibration, and by constituting the base or bed 2 a carrier for the wheel 4, the latter will be sustained in a substantial, stable manner and 70 its vibration effectually received and taken up by the heavy bed. This grinding wheel is fastened in some suitable manner to the shaft 5, the base or bed 2 having on its top bearings for sustaining the shaft in question. 75 Extending transversely of the bed 2 near the rear thereof is the main shaft 6 adapted to be rotated in any desirable manner. For instance, said shaft might be equipped with a pulley 7 connected by a belt 80 8 with a drum or pulley on an overhead or countershaft (not shown). The shaft 6 and therefore, the grinding wheel 4 are preferably, although not imperatively, continuously rotative.

The carrier 3 for the work is mounted for movement about an axis, being adapted as shown for swinging movement. While the tool is upon a stationary carrier and the work upon a movable carrier, this may not 90 in all cases be necessary, although it is desirable, an advantage having already been stated for the mounting of the grinding wheel 4 upon the base or bed 2. The carrier 3 as shown is in the form of a yoke, the 95 width of the body of which slightly exceeds the length of the base or bed 2. The branches of the yoke-like carrier 3 in the construction shown straddle the lower front portion of the base or bed and through them 100 the stationary shaft 9 freely extends, said shaft constituting a suitable pivot upon

which the carrier 3 can be swung back and forth, the work as represented and as will hereinafter more particularly appear, being carried upon the top or free portion of said carrier 3. By employing a swinging carrier such as 3, I can reduce the number of joints as compared with those present in a slideable carrier and can rotate the work or its equivalent by means of belting which in itself is of importance. Owing to the belt drive I can swing the carrier 3 inward or outward without in any manner affecting the driving connections.

The upper portion of the carrier 3 is shown provided with a head stock 10 and a tail stock 11 adjustable longitudinally of said upper portion in slideways such as are common in metal working machines of various kinds. The head stock 10 is provided with a fixed center 12 while the tail stock 11 is equipped with a practically similar center 13 between which the work is mounted. Although the work is preferably rotated it does not in the construction shown, receive its motion from either of the centers 12 or 13, both of which as noted being fixed or stationary. Extending longitudinally of the upper portion of the carrier 3 is a shaft 14 provided with a pinion 15 fastened thereto in some suitable manner for sliding movement thereon. The pinion 15 is in mesh with the spur gear 16 in the head stock 10, said spur gear 16 being equipped with an outwardly extending stud or projection 17 to which a so-called "lathe dog" can be connected to turn the work mounted between the centers 12 and 13. The outer end of the shaft 14 is equipped with tight and loose pulleys 18 and 19 to receive the belt 20 connected with the small and wide-faced step of the cone pulley 22 loose on the shaft 9 about which it will be remembered the carrier 3 turns. If the belt 20 be on the pulley 18 and if the pulley 22 be turned, it follows that the shaft 14 will be turned as will also through the intermediate parts, the spur gear 16 to effect the revolution of the stud 17, and if work be mounted between the centers 12 and 13 and if a latch dog be cooperatively interposed between the projections 17 and the work, the latter will be rotated. Rotation of the work can be stopped by moving the belt 20 from the tight pulley 18 to the loose pulley 19. Around the large step of the cone-pulley 22 is a crossed belt 23 which also passes around the pulley 24 on the main shaft 6 which provides a simple way of rotating said cone pulley from said main shaft. It follows as a consequence that if the shaft 6 be rotated and if the belt 20 be on the pulley 18 as explained and if the work be connected with the spur gear 16 in the manner already noted, the work will in such case be turned.

65. The work carrier 3 is provided with a

steady-rest denoted in a general way by 25 and made the subject matter of a contemporaneously pending application filed October 21, 1915, Serial No. 57,101. The pulleys 18 and 19 may as shown be incased by 70 the housing 26 on the carrier 3 while the bed may be furnished with a housing 27 to receive and protect the belt 23, the pulley 24 and the cone pulley 22.

Any suitable means may be provided for 75 giving to the carrier advancing and retracting movements. For this purpose I provide a feed nut and coöperating screw, the carrier 3 in the present instance being provided with the screw while the nut is upon the 80 base or bed 2. A feed screw such as meets the desired conditions is that denoted by 28, the coöperating nut being designated by 29, the base or bed being chambered as at 30 to receive the nut and forward portion of the 85 feed screw. Opposite sides of the chamber 30 are equipped with coaxial pins 31 adapted to enter sockets in the opposite sides of the nut 29 from which as will be inferred, said nut is mounted for tilting movement, 90 so that it can automatically compensate itself for the various angular positions of the carrier 3. The body portion of the carrier 3 has a chamber or cavity 33 to receive a bearing as 34 for the shaft 28, said bearing 95 34 as shown consisting of a collar through which the plain portion of the screw 28 freely extends, opposite sides of the bearing or collar 34 having sockets to receive the plain inner ends of the coaxial pivot screws 100 35. The collar 34 is also tilttable so that it can accommodate itself automatically to the different angular positions of the carrier 3. It will be clear that the nut 29 is immovable in the direction of the axis of rotation of the 105 screw 28.

It will, therefore, be obvious that if the screw 28 be turned in one direction the carrier 3 will be advanced, whereas on opposite rotation of the screw retraction of the 110 carrier will follow. In the present case the screw is turned to the right to advance the carrier and to the left to retract it. To thus operate the screw any suitable means may be provided, the hand wheel 36 being shown 115 for the purpose. In conjunction with the hand wheel is a suitable gage, one form of which will be hereinafter more particularly described. The base 2 is shown provided with a spring actuated plunger 37, the push 120 spring 38 of which and the plunger itself being in a socket in the base or bed. The operative or outer end of the plunger applies a constant effect to the carrier 3 to take up backlash and to prevent chattering.

In operation the work is mounted upon the carrier when the latter is in its retracted position and when the work is positioned it and the wheel 4 will be rotated and the wheel 36 will be manipulated to effect the 125 130

advance of the carrier to move the work against the surface of the wheel, the carrier being fed inward as the reducing operation progresses and until the work is reduced to the desired extent.

Fastened to the periphery of the hand wheel 36 is the gage or scale 39 with which the pointer or finger 40 is coöperative, the shank 41 of said pointer or finger having a clamp 42 and a counterweight 43. The clamp 42 is adapted to surround and to frictionally embrace the hub of said hand wheel. The counterweight 43 tends to normally maintain the shank or body portion 41 in an approximately vertical position. The pointer 41 in addition to coöperating with the scale or gage 39 also operates with the stop 44 pivoted to the bracket 45 on the base or bed 2. This stop 44 is normally in the path of the lug or projection 47 on the pointer 40 and when the lug strikes the stop as the hand wheel 36 is turned in feeding the carrier 3 inward, this indicates that the work has been reduced to the correct size or approximately so, which fact will be indicated by the scale 39. Provision is made for slip of the pointer 40. As I state the pointer 40 is arrested by the stop 44 when the work has been reduced or practically so, to the requisite size. When the pointer does strike the stop, this will apprise the operator of the fact noted. He can measure his work, and if it is not exactly reduced, he can advance the carrier 3 farther inward through the primary agency of the hand wheel 36 in the manner indicated, and during this motion the shank or body portion 41 will slip on the hub of the hand wheel. Said shank 40 or body portion 41 is provided with the wedge shaped part 46 generally integral therewith and which when the wheel 36 is reversely operated as shown by the arrow and dotted lines in Fig. 5 will strike and lift the stop 44 as illustrated by dotted lines in Fig. 2.

To shift the belt 20 a shifter such as that denoted in a general way by 20' may be provided.

As already noted the work carrier in the organization illustrated is forked at its lower end to straddle the bed 2, the consequence being that the lower portion of the bed constitutes a means for preventing lateral movement of the work carrier or movement thereof in the direction of the axis of rotation of the work which is an important feature when the machine is adapted for spotting, an operation which is of a precise character. The pivoting of the work carrier to the lower portion of the base is also a feature of some importance when it is considered that the work is supported by the upper portion of the carrier and that the tool is sustained by the upper portion

of the bed. The result of this is that the operator standing in front of the machine can get an unobstructed view of the work.

What I claim is:

1. A machine of the class described comprising a bed, means on the bed for rotatively supporting a grinding wheel, a work carrier pivotally connected with the bed for swinging movement, spindles on the work carrier for supporting the work, means independent of the spindles for rotating the work, and means for advancing the work carrier.

2. A machine of the class described comprising a bed, a grinding wheel supported by the bed, a work carrier pivotally connected with the lower portion of the bed for swinging movement, spindles on the work carrier above its point of support, for receiving between them the work, and a steady rest connected with the work carrier between said spindles, for engaging the work between the spindles, means for advancing said carrier, and means for rotating the work.

3. A machine of the class described comprising a bed, a grinding wheel on the bed, a work carrier pivotally connected with the bed for swinging movement, spindles on the work carrier for supporting the work, means independent of the spindles for rotating the work, manually operable means for advancing the work carrier, and means for positively preventing movement of the work carrier in the direction of the axis of rotation of the work.

4. A machine of the class described comprising a tool carrier, a swinging work carrier, a belt driven element coaxial with the work carrier, a belt driven element on the work carrier coöperative with the other belt driven element, work rotating means actuated by said second belt driven element, and a nut and a feed screw device, for advancing the work carrier, one of the elements of said nut and feed screw device having a swinging connection with the work carrier and the other having a swinging connection with the frame of the machine.

5. A machine of the class described comprising a bed, means for rotatively supporting a grinding tool on the bed, a swinging work carrier, a belt driven element coaxial with the work carrier, a belt driven element on the work carrier coöperative with the other belt driven element, work rotating means actuated by said second belt driven element, and means for advancing the work carrier.

6. A machine of the class described comprising a bed, means on the bed for rotatively supporting a tool, a swinging carrier provided with work supporting means, forked and straddling the bed, a pulley on the bed coaxial with the carrier, and a pulley

4

on the carrier, provided with means for rotating the work and coöperative with the other pulley.

7. A machine of the class described comprising a carrier, means including a wheel for moving said carrier, a gage disposed circumferentially of the wheel, a pointer coöperative with the gage and having a slip connection with the wheel, and a stop supporting independently of the wheel and in the path of the pointer.

8. A machine of the class described comprising a tool carrier and a work carrier, the latter being pivotally connected with the former for swinging movement, manually operable means for advancing the work carrier, and means for positively indicating to the operator of the machine, when said work carrier has advanced a certain distance.

20 9. A machine of the class described comprising a bed provided with means for rotatively supporting a grinding wheel, a carrier having a pivotal connection with the bed and provided with means for rotating the work, manually operable means for advanc-

ing said carrier, and adjustable means for positively indicating to the operator of the machine, when said carrier has been advanced a predetermined distance.

10. A machine of the class described comprising a bed provided with means for rotatively supporting a grinding wheel, a carrier pivotally connected with the bed for swinging movement and provided with means for rotatively supporting the work, a manually operable element provided with means for advancing said carrier, a manually settable element connected with said manually operable member by a slip connection, and a fixed device to be engaged by said manually settable element on a predetermined motion of the manually operable member.

In testimony whereof I affix my signature in presence of two witnesses.

BENGT M. W. HANSON.
